UNITED STATES PATENT OFFICE.

GEORGE C. MUIRHEAD, OF WORLAND, WYOMING.

ERASER.

Application filed April 5, 1923. Serial No. 630,150.

To all whom it may concern:

Be it known that I, GEORGE C. MUIRHEAD, a citizen of the United States of America, and a resident of Worland, in the county of Washakie and State of Wyoming, have invented a new and Improved Eraser, of which the following is a description.

My invention relates to erasers and more particularly to an eraser employing a rotary erasing blade and a clamp presenting jaws adapted to permit rotation of the blade for bringing a new edge portion thereof into a given position for use or to hold the plate against turning after a given adjustment of the blade.

The invention particularly relates to an eraser in which the blade and clamp are so related that the blade projects a gradually increasing distance beyond the adjustment clamp edges.

The general object of my invention is to provide a novel clamp means so formed and so associated with the steel or like cutting blade that the maximum edge portion of the blade is made available for erasing and the gradually increasing projection of the blade is continued for more than a half circle of the cutting edge.

A further object of the invention is to provide a burnishing means in association with the cutting edge of the blade.

The manner in which the above and other objects are attained, will clearly appear as the description proceeds.

Reference is to be had to the accompanying drawings forming a part of this specification, it being understood that the drawings are merely illustrative of two examples of the invention.

Figure 1 is a side elevation of an eraser embodying my invention;

Figure 2 is a central longitudinal section thereof;

Figure 3 is an end elevation on an enlarged scale of the edge portion of the clamp and eraser with a fragment of paper exaggerated to show the mode of functioning of the burnishing clamp edges in an erasing operation;

Figure 4 is a side elevation of the eraser showing a slightly modified form of clamp.

Referring at first more particularly to Figures 1 and 2 the form of the invention shown in said figures includes a round eraser blade 10 advantageously formed of steel and made with a keen cutting edge. The blade

is held in a holder in the form of a clamp 11 made of a length of flat metal doubled on itself and embraced by a slideable band 12. The sides of the clamp 11 tend to separate slightly but upon moving the slide 12 to a forward position the sides firmly clamp the blade 10 in position. The front terminal portions of the sides of the clamp 11 form jaws 15. On one jaw 15 is a lateral stud 13 adapted to project through a central pin hole in the blade 10 and into a registering hole 14 in the opposite side of the clamp 11.

The relative form and arrangement of the jaws 15 and blade 10 is such that said blade projects an increasing distance beyond the end edges of the clamp 11 from one side of said clamp to the other. In Figure 1 the pivot pin 13 of the blade 10 is eccentrically positioned in the clamp while the pin hole in the blade 10 is central so that there is an eccentric relation between the rounded jaws and said blade. The end edges of the jaws 15 are in the true arc of a circle. In order to obtain the maximum available cutting edge on the blade 10 beyond the clamp jaws 15, I continue the curvature of the end edges beyond the half circle, that is to say, rearward of the axis of the pin 13 and said rounded end edges of the jaws form a curvilinear angle with the body of the clamp 11. Adjacent the angle 16 the minimum projection of the blade 11 is attained, the degree of projection increasing about the end of the jaws toward angle 17 at the opposite side. The described formation not only gives the maximum available cutting edge on the blade 10 but it promotes efficiency in erasing at different angles, and is particularly effective in erasing from paper on the platen roller of a type writing machine.

In Figure 4 the clamp 111 provided with the described clamp band 12 and the same eraser blade 10 are provided as well as the pin 113 corresponding with the pin 13 and the pin hole 114 corresponding with the hole 14. Also, the end edges of the jaws 115 are rounded and form curvilinear angles at 116, 117 with the clamp 111. The clamp jaws 115, however, instead of having edges rounded in the true arc of a circle are spiral or on a curve the radius of which increases from one angle 117 toward the angle 116 at the opposite side, thereby obtaining the effect of the arrangement in Figures 1 to 3

of producing a maximum available cutting edge on the blade 10 while preserving the characteristic that at one side the blade projects to the minimum extent, and preserving the curvilinear angle 116 having in view erasures to be made in a paper on a platen roller for example.

The use of the round steel eraser is thus made practical and efficient to the highest degree. It will be readily understood that by sliding the clamp band 12 rearwardly to dotted line position in Figure 1 permits the blade to be adjusted should it become dull at one portion, the turning of the blade about its own axis serving to bring the cutting edge from beneath the clamp sides to a position for use. The described arrangement permits also the ready removal and renewal of the blade.

From Figure 3 it will be seen that the edges 18 of the clamp jaws 15 constitute burnishers at the sides of the cutting blade 10. The burnishing edge functions at that side of the jaws where the blade projects to a slight extent. Thus, the paper A indicated conventionally in Figure 3 may have an erasure made therein as shown exaggerated at *a* and it will be seen that as the blade slightly scrapes and penetrates the paper, either or both burnishing edges may be caused to smooth and polish the paper following the cutting action of the eraser blade. The increasing projection of the blade beyond the clamp edges makes possible a selectivity in the depth of the guarded blade.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. An eraser comprising a round steel blade formed with a cutting edge, and a holder formed with clamp jaws having pivot means on which said blade is centrally mounted and presenting curved edges at the front, said blade projecting beyond said front edges of the jaws to an increasing extent from the edge portion at one side of the pivot means toward the opposite side of said means.

2. An eraser comprising a round eraser element, and a holder formed with clamp jaws having pivot means on which said eraser element is centrally mounted and presenting curved edges at the front, said element projecting beyond said front edges of the jaws to an increasing extent from the edge portion at one side of the pivot means toward the opposite side of said means.

3. An eraser comprising a round eraser element, and a holder formed with clamp jaws having pivot means on which said eraser element is centrally mounted and presenting curved edges at the front, said element projecting beyond said front edges of the jaws to an increasing extent from the edge portion at one side of the pivot means toward the opposite side of said means, said curved edges of the jaws forming angles with the side edges of the body of the holder.

4. An eraser comprising a round eraser element, and a holder formed with clamp jaws having pivot means on which said eraser element is centrally mounted and presenting curved edges at the front, said element projecting beyond said front edges of the jaws to an increasing extent from the edge portion at one side of the pivot means toward the opposite side of said means, said curved edges of the jaws forming curvilinear angles with the side edges of the body of the holder.

5. An eraser comprising a round eraser element, and a holder formed with clamp jaws between which said element is turnably mounted, the end edges of the jaws being curved and the curvature continuing rearward of the pivot means, said element projecting beyond the jaws to the minimum extent at one side edge of the said jaws and projecting to a gradually increasing extent toward the opposite side.

6. An eraser comprising a round eraser blade, and a holder formed with clamp jaws accommodating said blade therebetween, said jaws having rounded edges to constitute burnishing means in association with the blade.

7. An eraser comprising an eraser blade presenting a rounded cutting edge, and a holder therefor, said holder comprising a member at a side of the blade and beyond which the blade projects to a varying degree, said member having a rounded burnishing edge.

8. An eraser comprising an eraser blade, and a holder formed with clamp jaws for said blade, the edges of said jaws being rounded and disposed inward from the cutting edge of the blade a distance for said rounded edges to constitute burnishers for burnishing and smoothing the paper in association with the cutting action of the blade.

9. An eraser comprising a round eraser element, and a holder formed with clamp jaws between which said element is turnably mounted, the end edges of the jaws being curved and the curvature continuing rearward of the pivot means, said element projecting beyond the jaws to the minimum extent at one side edge of the said jaws and projecting to a gradually increasing ex-

tent toward the opposite side, said curved edges of the jaws forming an angle with the side edges of the body of the holder.

10. An eraser comprising a round eraser element, and a holder formed with clamp jaws accommodating said element therebetween, means to bind the jaws in clamping relation on said element, and pivot means eccentrically positioned with respect to the 10 jaws and on which means said eraser element is centrally mounted, said eraser element projecting beyond the end edges of the jaws to an increasing extent from a point at one side edge and rearward of the 15 pivot means toward the opposite side of the pivot means.

11. An eraser comprising a round steel

blade formed with a cutting edge, and a holder presenting clamp jaws and having a pivot on which said blade is centrally mounted, the end edges of the jaws presenting a curve of increasing radius from one side edge to the opposite side edge and terminating at points rearward of the pivot pin, said curved edges of the jaws forming 25 curvilinear angles with the side edges of the body of the holder, and means to tighten the jaws on the blade or to permit turning movement of the blade, said blade projecting beyond the end edges of the jaws to 30 an increasing extent from the curvilinear angle at one side edge of the holder toward the opposite side.

GEORGE C. MUIRHEAD.
